DISTILLATION CONTROL

Merrell R. Fenske, State College, Pa., assignor to
Pennsylvania Petroleum Research Corporation,
a corporation of Pennsylvania

Application September 13, 1933, Serial No. 689,331

12 Claims. (Cl. 196—132)

This invention pertains generally to distillation, and particularly to a control therefor. It will be described in connection with the fractional distillation of mineral oils. However, it is to be understood that it is applicable to distillation processes in general.

In designing towers or columns, for instance for batch distillation, it is more or less the general practice to take into consideration the highest reflux ratio which will be required to separate the most difficultly separable fractions. When this reflux ratio is determined and chosen it will afford an adequate reflux for all fractions, but for all except the most difficultly separable fraction the reflux will obviously be more copious than is required, and the product will be taken off at a lower rate than is necessary. Furthermore considerable heat is wasted in the excessive reflux since it must be reevaporized and recondensed.

Since time is a very important element in the cost of operation it will be seen that unless some control of the reflux ratio is afforded the process must be regarded as being relatively inefficient.

A practice which has been followed to a considerable extent involves the manual control of the reflux ratio according to what the operator by experience determines to be appropriate for the particular fraction coming off at the moment. This at best can be no more than a mere approximation. Furthermore uniformity of results depends upon the operator's approximating ability remaining constant from the beginning to the end of his shift and from day to day, and when different operators control the same piece of equipment, upon their respective approximating abilities being the same. It can be seen that under this practice a really satisfactory control is not realized since it is too largely dependant upon the human element.

In the fractionation of compositions such as mineral oils, particularly upon a plant scale, practically none of the fractions comprise a constant boiling substance. The selection of the desired reflux ratio or ratios for each fraction therefore, not only involves the time element but also the desired temperature spread in the product, for it will be recognized that the larger the reflux ratio the narrower will be the spread and vice versa.

By way of explanation, a constant-boiling substance might be either a pure chemical compound or any mixture of compounds whose vapor is of the same composition as the liquid.

A pure chemical compound is characterized by having a fixed boiling point at any given pressure.

A fixed boiling point is likewise a characteristic of a constant-boiling mixture but the pressure at which the vapor is of the same composition as the liquid is usually also fixed.

In other words a constant-boiling substance 5 might be defined as one whose initial boiling point and end boiling point are the same at a given pressure.

The temperature spread of a substance is the difference in temperature measured in degrees 10 between its initial boiling point and its end boiling point.

It follows that a constant-boiling substance has a zero temperature spread, whereas a mixture of compounds whose vapor is not of the same composition as the liquid (and therefore separable by fractional distillation) has a temperature spread greater than zero.

A feature of this invention therefore relates to an accurate reflux ratio control. 20

A further feature relates to a control which affords a product of the desired temperature spread.

A further feature of the invention relates to a new and novel process and apparatus for the 25 automatic control of the reflux ratio for each fraction and of the temperature spread of the fraction.

A further feature of the invention relates to a control of the quantity of reflux and of the quantity of product, said control being responsive to the temperature spread of the product. 30

A further feature of the invention relates to a control for the reflux ratio which automatically varies the reflux ratio in accordance with requirements. 35

Further features of the invention reside in the construction, arrangement and combination of parts, and in the steps, and combinations and sequences of steps, all of which together with 40 other features will become more apparent to persons skilled in the art as the specification proceeds and upon reference to the drawings in which:

Fig. 1 is a semi-diagrammatic illustration of 45 an embodiment of the invention.

Fig. 2 illustrates a modified form of control column.

Fig. 3 illustrates a further form of control column. 50

Fig. 4 illustrates a means for varying the resistance of the galvanometer circuit at different temperatures.

Fig. 5 illustrates means for obtaining different voltages across the galvanometer circuit. 55

Referring now more particularly to Figure 1 of the drawings at 10 is conventionally illustrated a distilling tower having associated therewith the usual condenser 11, a reflux line 12, and a product line 13. Exhausting means is also conventionally illustrated at 14.

All of the foregoing may be regarded as standard equipment. The exhausting means may or may not be used depending upon whether or not 10 tower 10 is to be operated at sub-atmospheric pressures.

The equipment illustrated is of the batch type. The invention, however, is equally applicable to the continuous type of equipment. In the latter 15 case a separate control column controls the temperature spread of each product stream taken off.

The reflux ratio is of course the ratio of the reflux to the product. For a given amount of condensate delivered by condenser 11 the smaller the 20 amount of product drawn off the larger will be the amount of reflux as well as the reflux ratio, and vice versa. It follows that the reflux ratio may be controlled by controlling the rate at which the product is withdrawn from the system. 25

In a normally controlled system, as previously pointed out, the rate of withdrawal of product during the separation of any fraction is a matter of guess work and there is no accurate control of 30 the temperature spread of the fraction.

In accordance with this invention the temperature spread of the product (or a fixed part or parts thereof) is employed to control the rate at which the product is withdrawn. The temperature spread of the product may be set at any desired value. For a constant boiling liquid fraction it will obviously be zero. For fractions having finite boiling ranges the spread may be held constant at any desired value up to the point 40 where no reflux is returned to the tower. In other words the reflux ratio may be varied between infinity, in which case there would be no product and all the condensate would return as reflux, and zero, in which case there would be no 45 reflux and all of the condensate would be removed as product.

The term "temperature spread" for the purposes of this specification and the claims will include a zero spread, and the terms "phase composition differential" and "temperature differential" to be hereinafter employed includes a zero differential.

The control of the temperature spread of the product is accomplished through the use of a 55 control column through which at least a portion of the product flows preferably (though not necessarily) continuously on its way to the receiver or other destination. The product as it passes through a suitable receptacle or still at the bottom 60 of the column is maintained at a boiling temperature. The vapors pass up through the column, which has a suitable number of theoretical "perfect plates" for instance between 4 and 10, and the phase composition differential (which 65 will be referred to hereinafter as being measured in terms of temperature differential) between vertically spaced points in the column, for instance between the top and bottom, is employed to control a valve in the product line. The valve 70 in the product line controls the rate of flow of product and thus the reflux ratio, which in turn determines the temperature spread.

By "phase composition differential" is meant 75 difference in composition within either or both phases between points spaced longitudinally of

the control column. This may be zero or greater than zero.

By "temperature differential" is meant difference in temperature within either or both phases between points spaced longitudinally of the control column. This may be zero or greater than zero. 5

In the case of a mixture whose vapor is not of the same composition as the liquid at the pressure obtaining in the control column each phase is 10 caused to vary in composition longitudinally of its flow as the normal result of fractionation, each phase becoming richer in the lighter constituents from the bottom to the top of the column. As a result the temperature decreases 15 from the bottom to the top of the column.

In the case of a constant-boiling substance, since separations cannot be made by fractionation, each phase remains uniform in composition and the two phases are of the same composition 20 throughout the control column. As a result the temperature is uniform from the bottom to the top of the column.

Since the temperature differential between any two longitudinally spaced points in the control 25 column is a measure of the phase composition differential between these two points, for purposes of simplicity in description temperature differential will be referred to.

For a constant boiling fraction both the temperature differential and temperature spread will be zero. For a fraction which is further separable by fractionation the temperature differential will have a value greater than zero and will be dependent upon the temperature spread of 30 the product flowing through the receptacle. By closing the valve (partially or completely) when the temperature differential and consequently the temperature spread is larger than desired and opening the valve (partially or completely) 35 when the temperature differential and consequently the temperature spread is smaller than is desired, the reflux ratio is automatically varied according to the requirements for separation of the fraction. As a result the capacity of the 40 equipment is increased and each fraction is taken off with a desired temperature spread. This spread need not be the same for each fraction, but may be different as will hereinafter appear. 45

Referring to Figure 1 of the drawings at 16 is 50 illustrated a flask having a relatively long stem 17 and a bulb 18. The upper portion of stem 17 is surrounded by a condenser 19 and above the condenser a branch tube 20 is illustrated. Bulb 18 at its bottom communicates with an S-shaped 55 draw off tube 21, the highest point 22 of which is so positioned with respect to bulb 18 as to maintain a desired liquid level in bulb 18.

Stem 17 contains a suitable column packing 60 material which is illustrated as being supported by a helical spring 24 having its ends 25 fused into the walls of stem 17. In order that the control column may be compact and yet contain a reasonable number of perfect plates, I prefer to use a packing material 26 which requires a 65 very small height per theoretical plate, for instance single helical turns of about $\frac{1}{4}$ inch diameter and small pitch made from very small diameter rod and of any suitable material such as metal or glass. However, any other packing may be employed. In fact any type of column may be adapted to this particular use. 70

A tube 28 communicates with stem 17 below condenser 19 and adjacent the top of packing 26. Tube 28 is connected to product line 13 on 75

the outlet side of an electrically controlled valve 29 in said product line. The connection of tube 28 to line 13 is such that product will flow therethrough in preference to continuing through line 13. Any means may be provided for this purpose, for instance such as that illustrated. An adjustment screw or valve 30 is provided in tube 28 so that the flow therethrough may be regulated. The rest of the product flowing through valve 29, of course, continues on through line 13 and is delivered to any suitable destination, for instance, a receiver illustrated at 31.

Valve 29 is provided with a constant flow orifice 32, which is controlled by an adjustment screw 33, and a variable flow orifice of substantially greater capacity 34 which is controlled by a movable valve element 35 operated by solenoid 36.

The flow through orifice 32 need only be substantially just sufficient to keep the tube 28 filled, since it is primarily provided so that the control column may be supplied with condensate even though the orifice 34 is closed.

Any means may be provided to respond to the temperature differential between desired vertically spaced points in the control column. For instance a thermocouple junction may be positioned at each point and a galvanometer may be connected in series with these junctions and may be made to respond to any current set up by a difference of temperature at the junctions. The relative position of the responsive element of the galvanometer may be made to control an external circuit which may be made to operate the solenoid 36.

Such an arrangement is shown in the drawings wherein a single strand of wire (which may be bare if the packing 26 is non-conductive) is shown threaded down through stem 17 and out through bulb 18. This strand of wire between terminals 38 and 39 is composed of two different suitable metals or alloys of metals, the portion 40 between junctions 41 and 42 being of one metal and the portions 43 and 44 being of the other metal. If the remainder of the circuit is composed of a metal other than that of the portions 43 and 44 the terminals 38 and 39 should obviously be maintained at substantially the same temperature, which may be room temperature.

The remainder of the circuit as shown comprises wire 46 in which is inserted rheostat 47, coil 48 of galvanometer 49 and wire 50. Galvanometer 49 is of a well known type and is merely illustrated diagrammatically. An essential feature of galvanometer 49 is that coil 48 rotates in response to and through an arc proportional to current flow, and returns to its original position upon the cessation of such flow. Coil 48 carries a mirror 51 which is adapted to reflect a beam of light from a light source 52 in the general direction of a photoelectric cell 53, said beam being directed on or off of said cell depending upon the position of coil 48.

Since it is desired to concentrate the beam on the photoelectric cell for all values of current above a certain point, a stop 55 is provided for coil 48, said stop limiting the rotation of coil 48 in a manner to obtain these results.

Cell 53 is a part of a vacuum tube relay circuit. This circuit comprises a three element tube 57 having a plate 58, a grid 59, and a filament 60. The filament is illustrated as being supplied with alternating current from a transformer 61 for the purposes of heating. The conventional po-

tentiometer 62 with sliding tap 63 is shown connected across the filament terminals, the tap being connected to the minus B terminal.

The input circuit includes a potentiometer 64 connected across a suitable voltage source with the plus terminal connected to the filament through tap 63 and potentiometer 62. Potentiometer 64 has two sliding taps 65 and 66, tap 65 being connected to grid 59 through cell 53, and tap 66 being connected to grid 59 through the grid leak 67. Tap 65 is directly connected to the cathode 68 of cell 53 and grid 59 is directly connected to the anode 69 of cell 53. The particular photoelectric cell illustrated is of the photo-emissive type.

A relay 71 is connected in the output circuit and is operated thereby. As illustrated armature 72 breaks a circuit through contacts 73 and 74 when the relay is energized and makes a circuit through these contacts when the relay is deenergized.

The circuit of contacts 73 and 74 comprises wire 75, battery 76, wire 77, solenoid 36, wire 78 and armature 72.

The operation of the device shown in Figure 25 1 is as follows:

Assuming the distillation equipment to be in operation, product will flow through pipes 13 and 28 into and down through the control column and into bulb 18, where it will be brought to a boiling temperature by any suitable heating means. Such means has been illustrated as a heating element 80, connected across a source 81 through a current control 82. The vapors ascend through the control column and if the product is further separable by fractionations rectification takes place with the result that points 41 and 42 will have a different temperature. The temperature differential between points 41 and 42 will of course depend upon the temperature spread of the product. If the temperature spread is zero as in the case of a constant boiling liquid, the temperature differential will also be zero. If the temperature spread has some value above zero, the temperature differential will also have a value above zero and proportional to the temperature spread.

A difference in temperature at points 41 and 42 generates an electromotive force which causes a current flow through the galvanometer, and coil 48 rotates through an arc proportional to the current flow. Whether or not the beam of light will be brought to rest upon the photoelectric cell 53 will depend upon the value of the temperature differential and the setting of the instrument. The setting is accomplished by means of rheostat 47 which controls the amount of current for any temperature differential. The beam of light is brought to rest on cell 53 when and as long as the desired temperature spread is exceeded, whether it be zero or of a finite value.

The relay circuit is so arranged and adjusted that when cathode 68 is not energized, sufficient current may flow through the output circuit to energize relay 71 to hold contacts 73 and 74 apart. This permits orifice 34 to remain open and product may flow freely therethrough. Current in the output circuit may be adjusted at tap 66 which controls the normal grid bias.

Let us assume that a temperature spread of 10° F. is desired in the product. In this case coil 48, by means of rheostat 47, would be set so that the light beam would fall just to one side of cathode 68 when the spread is at 10 degrees. Now should the spread increase beyond 10 de-

grees, the increased temperature differential would increase the electromotive force generated by the thermocouple which in turn would increase the current through galvanometer 49 to further rotate coil 48. This would bring the beam of light onto cell 53 thereby making the cell conductive. This would increase the grid bias in view of the position of tap 65 sufficiently to cut down the current in the output circuit to the point where relay 71 would be in effect deenergized. Orifice 34 would be immediately closed due to the release of armature 72 thereby causing contacts 73 and 74 to close the circuit through solenoid 36.

15 The closing of orifice 34 decreases the rate of flow of product and consequently increases the reflux ratio. A part of the product however flows continuously through the control column and as soon as the increased reflux ratio has 20 brought the product back to a 10° spread the light beam will move to one side of cathode 68. Orifice 34 will then open to increase the rate of flow of product. When the spread again exceeds 10° F. orifice 34 will close and the cycle 25 will be repeated.

In view of the high sensitivity of thermocouple and galvanometer circuits it will require only a very small change in the temperature differential to open or close orifice 34. This sensitivity may 30 be increased by increasing the spacing between the cathode 68 and the mirror 51, since the greater this spacing the smaller will be the necessary movement of coil 48 to bring the light beam on or off cathode 68. Since the product preferably 35 flows continuously and in very small amount through the control column, the fresh product will be brought to boiling immediately upon entering bulb 18 and the vapors and reflux of the control column will follow closely those of the 40 fresh products. As a result, the temperature differential will follow closely the temperature speed.

Condenser 19 is provided preferably to completely reflux vapors which flow up above the 45 control column. The complete reflux of these vapors prevents their escape and they are eventually delivered to receiver 31 as condensate. With a control column of the type shown in Figure 1 scrubbing is effected not only by condensate but 50 also by the fresh product. The fresh product in descending through the control column reaches a temperature close to boiling before it enters bulb 18.

The control of the flow of the product may of 55 course be accomplished in other suitable ways and different theories of operation may be devised. For instance in batch distillation it may be desired to set the opening at orifice 32 so that with orifice 34 closed the reflux ratio will be 60 such as to take care of the most difficultly separable fraction. In this case orifice 34 would control the reflux ratio for each of the other fractions as required.

The new product after flowing down through 65 the control column will comprise the upper stratum of liquid in bulb 18, will cause the outflow of old product through tube 22 and will be the first to vaporize. All of the fractions are completely miscible and therefore there will be 70 no separation due to differences in density.

Although it is preferred to pass only a small part of the product through the control apparatus for the reasons set forth above, any portion or all of the product may be so employed without 75 departing from the spirit of the invention.

In the above description it has been assumed that the distilling apparatus is being operated at atmospheric pressure. Therefore the mouth of stem 17 has been described as being open. In this case any change in atmospheric pressure will affect the distilling column and the control column equally and the precision of the control will remain the same.

When operating with sub-atmospheric pressures the mouth of stem 17 is closed, for instance 10 by a cork 84 (through which passes the wire 43) and the control column is exhausted to the same extent as the distilling column by the vacuum apparatus 14. This is illustrated by connecting tube 85, which connects with tube 20, to vacuum line 15 86. Line 86 connects the output side of condenser 11 to vacuum apparatus 14.

For any distillation above atmospheric pressure the control column would also be operated at the same pressure as the distilling column. 20

Many other modifications might be devised by persons skilled in the art upon becoming familiar with this invention. For instance it will at once occur to a skilled electrician that the external circuit may be varied in a vast number of ways to 25 accomplish a control of the rate of flow of product.

A different type of control column is shown in Figure 2 in which the flask 90 has a stem 91 without a product inlet and a bulb 92 having an inlet 30 93 at the bottom, and an overflow 94 at the side. Otherwise the control column of Figure 2 is essentially the same as that shown in Figure 1.

In operation the product enters at 93 and overflows at 94 and is kept boiling while in bulb 92. 35

In any case the volume of liquid in the bulb is preferably small so that this volume may at all times be representative of the product coming off.

A further type of control column is illustrated 40 in Figure 3, in which flask 96, comprises a stem 97 and a bulb 98. Bulb 98 has an S-shaped overflow 99 similar to that of bulb 18 of Figure 1.

Stem 97, at its top 100, is connected and sealed to a relatively larger portion 101 having a product inlet 102 at its top 103. A tube 104 has a portion 105 which extends down into portion 101 through its top 103 to which it is sealed. Tube 104 is substantially axially aligned with stem 97 and has an end 106 which is spaced from the end 100 of stem 50 97.

Tube 104 is provided with a condenser 107, a side tube 108 for connection to vacuum apparatus, and may or may not be closed with cork 109 depending upon whether the distillation is at sub-atmospheric or atmospheric or superatmospheric pressure as previously described. 55

In operation the product enters at 102 and flows down around portion 105 of tube 104 before it enters the top of the column at 100. Vapors 60 from the column ascend into tube 104 and are at least partially condensed in portion 105 since the product will generally enter at a temperature below boiling. The heat transfer to the product raises the temperature thereof so that it enters 65 the column at a temperature nearer boiling. If all of the vapor is not condensed in portion 105 the rest is preferably completely condensed by condenser 107. The latter form of flask is preferred if the product becomes substantially cooled 70 before it reaches the control column.

According to the previous description, as long as the setting at rheostat 47 remains constant the fraction or fractions will come off with a temperature spread which will not vary substantially, 75

depending of course upon the care with which the apparatus is constructed. If it is desired to change the temperature spread for any fraction it is merely necessary to adjust rheostat 47, to 5 reduce the resistance of the galvanometer circuit if it is desired to narrow the spread, or to increase the resistance if it is desired to widen the spread.

Since the temperature differential is proportional 10 to the temperature spread it is possible to operate a pyrometer with the same, but preferably with a separate, thermocouple. The pyrometer may then be calibrated in terms of temperature spread. This is illustrated in Figure 1 15 of the drawings wherein the previously described thermocouple parts are shown duplicated and the circuit thereof is closed through a pyrometer illustrated at 111. It is, of course, obvious that the two thermocouple circuits should be insulated 20 from each other and any suitable means known in the art may be provided for this purpose.

If the pyrometer 111 is employed the results of a change in resistance at 47 may be read directly on the pyrometer, time of course being allowed 25 to permit the main column to adjust itself to the change in average reflux for the particular fraction coming off.

It is, of course, possible to control any other device or instrument by means of the temperature 30 differential between spaced points in the control column.

As previously pointed out, the control is equally applicable to either batch or continuous distillation. In the case of continuous distillation each 35 product stream whether taken off at the top or at the side of the column has its temperature spread controlled by a separate control column in the manner above described. Thus the temperature spread of each product may be varied independently 40 of the other products.

Although it is preferred that the product flow continuously through the control column so that the character of the liquid therein may follow closely that of the product, this is not an absolutely essential feature. For instance the control 45 column might be employed only at intervals to adjust the rate of flow of the product, as by setting the opening of a valve or otherwise, or the control column might be employed to operate any 50 other type of transmitting means such as an indicator or gauge from which the rate of flow of product might be controlled normally. The pyrometer 111 is an example of the latter. Or the control column may be employed merely to make 55 a record of the temperature spread as by operating pyrometer 111, many types of which are adapted to make permanent records.

When using the batch method it may be desired to change the temperature spread of succeeding 60 fractions automatically. To accomplish this it is merely necessary to automatically vary the resistance of the galvanometer circuit as the temperatures which bound the fractions are reached. Any suitable arrangement may be provided for this purpose.

In Figure 4, for instance, is shown at 112 a plurality of well known temperature controlled switching devices 113, 114, 115, and 116. Each 65 of said switching devices 113 to 116 has an element responsive to temperature (not shown) which is inserted in the vapors at the top of the main column or between the main column and the condenser as illustrated at 112 in Figure 1.

As is well known these switching devices rotate 70 through an arc when a certain temperature is

reached. This temperature may be set at any desired value. The rotatable element of each switch 113 to 116 comprises a disc-like member 117, 118, 119, and 120 respectively. Each disc-like member, as illustrated, carries two mercury switches, member 117 carrying switches 121 and 122, member 118 carrying switches 123 and 124, member 119 carrying switches 125 and 126, and member 120 carrying switches 127 and 128. All of the switches are shown in cold position.

Switches 122, 124, 126, and 128 are inserted in a common series circuit between terminals 129 and 130. This circuit comprises resistance 137, wire 131, resistance 136, switch 122, wire 132, switch 124, wire 133, switch 126, wire 134, switch 15 128, and wire 135. Switches 122, 124, 126, and 128 are closed in the positions shown.

Switches 121, 123, 125, and 127 are shown in open position. Switch 121 controls a circuit between wire 131 and wire 132 which circuit includes a resistance 138. Switch 123 controls a circuit between wire 131 and wire 133, which circuit includes a resistance 139. Switch 125 controls a circuit between resistance 137 and wire 134. Switch 127 controls a circuit between terminal 129 and wire 135 which circuit includes a resistance 140. Switching devices 113, 114, 115, and 116 respond in order as the temperature increases and for the purposes of illustration it will be assumed that switching device 113 rotates at 200° C., switching device 114 at 250° C., switching device 115 at 300° C. and switching device 116 at 350° C. No particular significance is attached to the temperatures chosen, to the number of switching devices employed, or to the sequence 35 in which the temperature spread is increased or decreased, all of which are described in detail for the purposes of illustration.

The device of Figure 4 may be connected in series with the galvanometer circuit in any suitable manner, for instance by opening the circuit at point 142 on wire 50, and inserting a single pole double through switch 143, which in one position connects the ends 144 and 145 of wire 50 directly and in the other position connects the terminals 129 and 130 in series between ends 144 and 145.

The rheostat 47 is adjusted so as to afford the desired temperature spread for the fractions which come off under 200° C. When 200° C. is reached switching device 113 rotates clockwise. 5 This opens switch 122 thus breaking the previously closed circuit between wires 131 and 132, and closes switch 121, thus closing a new circuit between wires 131 and 132 through resistance 138. The effect of this is to substitute resistance 138 for resistance 136. Resistance 138 may be of any desired value and will be larger than resistance 136 if the temperature spread is to be larger between 200° C. and 250° C. or is smaller if the spread is to be smaller. Resistance 138 may be fixed or variable but preferably has a set value with respect to resistance 136 so as to automatically set the device for the desired new spread without further adjustment.

When the temperature reaches 250° C. switching device 114 rotates clockwise. This opens switch 124 and thus the previously existing circuit between wires 131 and 133 through resistance 138 is broken. This also closes switch 123 thus closing a new circuit between the same wires through resistance 139. The net effect of this is to substitute resistance 139 for resistance 138. Resistance 139 may be larger or smaller according to the temperature spread desired between 250° C. and 300° C.

Upon reaching 300° C. switching device 115 rotates clockwise. Switch 126 opens to open the previously established circuit through resistance 139 and switch 125 closes to directly connect resistance 137 to wire 134. The net effect of this is to reduce the resistance between terminals 129 and 130 below that of the first circuit by the amount of the resistance 136. The spread will obviously be narrower than at any time previous.

When 350° C. is reached switching device 116 rotates clockwise to open switch 128 and close switch 127. The opening of switch 128 opens the previously established circuit between terminals 129 and 130 and the closing of switch 127 directly connects terminals 129 and 130 through resistance 140. The net effect of this is to substitute resistance 140 for resistance 137. If resistance 140 is smaller the spread will be made still narrower. If resistance 140 is larger the spread will be larger than just previous and obviously may be of any desired value.

No attempt has been made to exhaust all of the possible combinations of resistances and switches which are unlimited. From the foregoing it will be seen that any desired sequence of temperature spreads may be obtained.

Switches 113, 114, 115, and 116 return automatically to their original positions when the temperature drops back below 200° C., 250° C., 300° C., and 350° C. respectively. Since a fall in temperature below 200° C. generally accompanies the charging of a new batch, the device will automatically set itself to repeat the foregoing sequence with the new batch.

Other means may be provided to obtain the desired sequence of temperature spreads. For instance it is possible to vary the resistance of the galvanometer circuit at desired time intervals by means of clock mechanism. However, varying the resistance with the temperature at certain temperatures is to be preferred in batch distillation.

A means for obtaining different voltages across the galvanometer is illustrated in Figure 5. In this figure flask 16 of Figure 1, and its appurtenances have been substantially reproduced except for the thermocouples 147, 148, 149, and 150. Each of the latter thermocouples has a pair of junctions 151, 152, 153, and 154 respectively. The spacing between junctions is different for each pair. It follows that the temperature differential between each pair of thermocouple junctions will be different and consequently the voltage developed by each pair will be different. These different voltages may be availed of to vary the temperature spread by connecting selected thermocouples across the galvanometer. This may be done manually or automatically, for instance by a clock mechanism.

As illustrated in the drawings one set of thermocouple terminals is connected to a common terminal 156 and the terminals of the other set are connected to the spaced fixed contacts 157, 158, 159, and 160 respectively of a rotary switch 161. The galvanometer 49 is connected between the movable contact 162 of switch 161 and terminal 156.

The different voltages obtained from the thermocouples may be availed of for any desired purpose. For instance thermocouples 147, 148, 149, and 150 may be standardized so that the temperature spread of the product may be varied fixed amounts. For instance, the temperature spread might be 5° C. when thermocouple 147 is in circuit, 10° C. when thermocouple 148 is in

circuit, 15° C. when thermocouple 149 is in circuit and 20° C. when thermocouple 150 is in circuit.

Switch 161 may be operated manually for instance by the knob 164 or automatically for instance by the clock mechanism illustrated generally at 165. Any clock mechanism would be suitable and it is therefore not illustrated in detail. Knob 164 may correspond to the knob for manually setting the hand or hands when a clock mechanism is employed. This would afford both manual and automatic operation.

The invention in its broader aspects includes the rectification of any vapors of the character producing the product. Such vapors for instance not only include vapors of the product itself as it is drawn off from the column either in an overhead or side stream, but also the vapors passing up through the main column which after being rectified and condensed form such product. The temperature differential between spaced points in the rectifying means for the particular vapors would then control the rate at which the product of such vapors would be withdrawn and consequently the reflux ratio affecting the particular product. In this case it is merely necessary to transfer the thermocouple to the proper section of the main column. Such section for each vapor is preferable one over which the vapor flows just prior to being condensed since it is then in a relatively pure state. For instance, the main column itself, or parts thereof might be used for the same purpose as the separate control column.

While the invention has been described in connection with the control of the flow of product from a distillation column it is to be understood that the invention may be employed for any purpose whatsoever. For instance, it would be possible to employ the control column to control the rate of condensation or the temperature spread of the condensate in any section of a fractional condensation system. In this case the column would control the rate of flow of cooling fluid through the particular section of the fractional condenser and thus control the temperature spread of the liquid condensed therein. A part of the condensate would of course flow through the column so that the proper spread might be maintained.

Other uses will suggest themselves to persons skilled in the art upon becoming familiar with this invention.

Several distillation columns might be controlled by a single control column particularly if their operation characteristics were substantially the same. The product of one column might control the operation of all columns or a part or all of the product of two or more columns might be mixed before entering the control column.

Although certain embodiments of the invention have been described in detail it is to be understood that the invention is not limited thereto. Therefore, changes, omissions, additions, substitutions and modifications may be made without departing from the spirit thereof, and the claims are intended to be limited only as required by the prior art.

I claim:

1. The combination with apparatus adapted for the fractional distillation of a liquid and having means for varying the temperature spread of the product produced thereby, of a device for controlling said means and thus the temperature

- spread of the product produced by said apparatus, said device comprising a control column, a still for said control column, means for continuously flowing at least a portion of said product produced by said first-mentioned apparatus through said still, means for vaporizing at least a portion of said product as it flows through said still, means for causing said product vapors to flow through said column countercurrently to liquid reflux under at least substantially adiabatic conditions, and means responsive to temperature differential between spaced points having at least a portion of the contacting section of said control column therebetween for controlling said first-mentioned means.
2. In combination, fractionating apparatus, means associated with said apparatus for controlling the temperature spread of the product produced thereby, a control column adapted to operate under at least substantially adiabatic conditions, means for delivering vapors of the character producing said product to said control column, means in said control column for subjecting said vapors to fractionating conditions, a plurality of means each responsive to temperature differential between a separate pair of spaced points in said column, the spacing between each pair of points being different from that of the others, means for selectively connecting a translating device to said means of said plurality of means, and means for connecting said translating device to said first-mentioned means for controlling the same.
3. A method comprising fractionating a liquid mixture under conditions in which the temperature spread between the initial and end points of a product of said fractionation is subject to variation through a control of said fractionation, subjecting vapors of said product to further fractionating conditions, measuring phase composition differential effected by said last mentioned fractionation, and controlling said first mentioned fractionation in accordance with increase or decrease in said phase composition differential so as to maintain substantially constant the temperature spread of said product.
4. In combination, means for fractionating a liquid mixture, means for varying the temperature spread between the initial and end points of a product of said fractionation, means for subjecting vapors of said product to further fractionating conditions, means responsive to change in phase composition differential between a pair of spaced points having at least a part of said last mentioned fractionating conditions therebetween, and means for connecting said last mentioned means to said second mentioned means to control said second mentioned means in accordance with increase or decrease in said phase composition differential so as to maintain substantially constant the temperature spread of said product.
5. A method comprising fractionating a liquid mixture under conditions in which the temperature spread between the initial and end points of a product of said fractionation is subject to variation through a control of said fractionation, subjecting vapors of said product to further fractionating conditions, measuring phase composition differential effected by said last mentioned fractionation, and controlling said first mentioned fractionation to maintain a substantially constant temperature spread of said product by causing said temperature spread to decrease when said phase composition differential increases above the value in phase composition differential at which the desired temperature spread is obtained and by causing said temperature spread to increase when said phase composition differential decreases below the value in phase composition differential at which the desired temperature spread is obtained.
6. In combination, means for fractionating a liquid mixture, means for varying the temperature spread between the initial and end points of a product of said fractionation, means for subjecting vapors of said product to further fractionating conditions, means responsive to change in phase composition differential between a pair of spaced points having at least a part of said last mentioned fractionating conditions therebetween, and means for connecting said last mentioned means to said second mentioned means in a manner to decrease said temperature spread with increase in said phase composition differential and to increase said temperature spread with decrease in said phase composition differential to maintain the temperature spread of said product substantially constant.
7. A method comprising subjecting vapors of the character producing a product of a fractionating tower to fractionating conditions by intimately contacting said vapors with countercurrently flowing liquid reflux in a contacting path, said vapors and said liquid reflux entering said contacting path at longitudinally spaced points, and controlling the degree of fractionation effected by said fractionating tower in producing said product through a phase composition differential measured between a second set of spaced points, said second set of spaced points being in said contacting path and bracketed by said first mentioned spaced points.
8. A method comprising separately subjecting vapors of a product of a fractionating tower to further fractionating conditions by intimately contacting said vapors with countercurrently flowing liquid reflux in a contacting path, said vapors and said liquid reflux entering said contacting path at opposite ends thereof, and increasing and decreasing the degree of fractionation effected by said fractionating tower in producing said product with increase and decrease respectively in a phase composition differential in said contacting path, said phase composition differential being measured between points spaced longitudinally of said contacting path and positioned between the points of entry of vapors and reflux liquid.
9. A method for controlling the temperature spread between the initial and end points of a product of the fractional distillation of a liquid mixture in which fractional distillation vapors of said liquid mixture are countercurrently contacted with liquid reflux comprising, subjecting vapors of said product to further fractionating conditions by intimately contacting said last mentioned vapors with countercurrently flowing liquid reflux in a separate contacting path, said last mentioned vapors and last mentioned liquid reflux entering said separate contacting path at opposite ends thereof, and employing difference in temperature between longitudinally spaced points in said separate contacting path to control the proportion of liquid reflux to vapors in said first mentioned distillation, said spaced points being positioned between the point of entry of said second mentioned vapors and the point of entry of said second mentioned liquid reflux into said separate contacting path.

10. A method for controlling the temperature spread between the initial and end points of a product of the fractional distillation of a liquid mixture in which fractional distillation vapors of said liquid mixture are countercurrently contacted with liquid reflux comprising, subjecting vapors of said product to further fractionating conditions by intimately contacting said last mentioned vapors with countercurrently flowing liquid reflux in a contacting path, said last mentioned vapors and last mentioned liquid reflux entering said contacting path at opposite ends thereof, and increasing and decreasing the proportion of liquid reflux to vapors in said first mentioned fractional distillation with increase and decrease respectively in temperature differential between longitudinally spaced points in said contacting path, said spaced points being positioned between the points of entry of vapors and liquid reflux into said contacting path.
11. The combination with fractionating apparatus having means for varying the temperature spread of a product produced thereby, of a device for controlling said means and thus the temperature spread of the product produced by said apparatus, said device comprising a control column, means for flowing vapors of said product through said control column countercurrently to liquid reflux, and means responsive to change in temperature differential between spaced points

having at least a portion of the contacting section of said control column therebetween for controlling said first mentioned means in a manner to decrease said temperature spread with increase in said temperature differential and to increase said temperature spread with decrease in said temperature differential. 5

12. The combination with fractionating apparatus having means for varying the temperature spread of a product produced thereby, of a device for controlling said means and thus the temperature spread of the product produced by said apparatus, said device comprising a control column, means for flowing vapors of said product through said control column countercurrently to liquid reflux, means responsive to change in temperature differential between spaced points having at least a portion of the contacting section of said control column therebetween for controlling said first mentioned means in a manner to decrease said temperature spread with increase in said temperature differential and to increase said temperature spread with decrease in said temperature differential, 10 15 20
